UNITED STATES PATENT OFFICE.

SAMUEL E. MORRAL AND WILLIAM W. MORRAL, OF MORRAL, OHIO.

CORN-HUSKING DEVICE.

1,388,286.

Specification of Letters Patent. Patented Aug. 23, 1921.

Application filed June 14, 1919. Serial No. 304,209.

To all whom it may concern:

Be it known that we, SAMUEL E. MORRAL and WILLIAM W. MORRAL, citizens of the United States, residing at Morral, in the county of Marion and State of Ohio, have invented certain new and useful Improvements in Corn-Husking Devices, of which the following is a specification, reference being had therein to the accompanying drawing.

10 This invention relates to corn husking devices and more particularly to ear removing devices which are used in connection with the husking devices.

15 The object of the invention is to provide a device of this kind with means for delivering a stalk of corn, with the ear attached, to the device which removes the ear from the stalk; and which will properly position the ear with respect to said removing 20 device.

25 A further object of the invention is to provide such a device which will separate the ear from the stalk and deliver the ear to the husking devices without mutilating the stalk.

30 A further object of the invention is to provide such a device which will be simple in its construction and operation and which can be produced at a relatively low cost.

35 In the accompanying drawings Figure 1 is an end elevation of a corn husking machine embodying our invention; Fig. 2 is a side elevation of the same, with the platform removed; Fig. 3 is a plan view of such 40 a machine; Fig. 4 is an end elevation of a machine embodying the invention in a slightly modified form; Fig. 5 is a plan view of the machine of Fig. 4; Fig. 6 is an end elevation of a machine embodying a further 45 modification of the invention; Fig. 7 is a plan view of the machine of Fig. 6; and Fig. 8 is a detail view of the ear removing device of Fig. 7.

50 In Figs. 1 to 3 of these drawings we have illustrated one form of our invention and have shown the same embodied in a corn husking machine comprising a main frame 1 upon which are mounted ear removing devices 2. These ear removing devices are arranged at a point remote from the forward edge of the frame and substantially midway between the ends thereof. The operator's 55 station is in front of the machine and the frame may, if desired, be provided with a supporting bracket 3 to support a quantity

of corn. Mounted on the frame and leading to the ear removing devices are suitable means for moving the stalks of corn one at a time toward the ear removing devices and for positioning the ear so that it will be 60 properly engaged by the ear removing devices and separated from the stalk. Means for so moving the stalk of corn may take various forms, but in that form of the device shown in Figs. 1 to 3 the ear removing devices 65 are in the form of snapping rollers and the conveyer for the stalks of corn comprises two oppositely rotating rollers 4 and 5 which are connected with the respective snapping rollers for rotation therewith. 70 The rollers 4 and 5 are arranged one above the other and, in the present instance, provided with spiral ribs forming grooves, which engage the stalk of corn and move the same lengthwise of the conveyer rollers 75 toward the snapping rollers and at the same time move the stalk transversely of the conveyer rollers to bring the butt of the ear into engagement with said rollers so that it will be in a proper position to be engaged 80 by the snapping rollers when the stalk has reached the end of the conveyer rollers. The conveyer rollers may be arranged in various ways, but in this form of the device the upper roller 5 is somewhat shorter than the 85 lower roller and has its outer end suspended above the lower roller and tapered so that a stalk of corn may be placed over the lower roller and moved between the two rollers into a position to be engaged by both rollers. 90 In the present construction the outer end of the upper roller is not provided with individual supporting means, but is supported solely by the bearing or bearings for the opposite end thereof. The main frame is provided with a table top 11 extending on opposite sides of the conveyer rollers to support the ends of the stalks of corn. The conveyer will move the stalks bodily across the table, but we prefer to provide supplemental conveying means to move the ends of the stalks so as to maintain each stalk in a substantially straight line. As here shown, the supplemental conveyers comprise sprocket chains 6 having fingers 7 and extending about sprocket wheels on shafts 8 arranged along the front and rear edges of the table and so mounted that the upper stretches of the conveyer chains will lie beneath the table top and the fingers 7 will 105 110

extend through slots in the table top and project above the same to engage the stalks of corn. When the ear has been separated from the stalk the latter is moved on past the snapping rollers and delivered beyond the rear edge of the table. As here shown, the main frame 1 is so shaped as to form a compartment 9 in which the stalks of corn are bunched. The separated ear drops through an opening in the table top, which is broken away in Fig. 3 and is delivered to suitable husking devices which are here shown as husking rollers 10. These rollers are arranged in an inclined position beneath the table top and act upon the ears of corn in a well known manner to separate the husks therefrom.

Any suitable driving mechanism may be provided for operating the several parts of the machine. As here shown, a main driving shaft 12 is mounted in the lower part of the frame 1 and has secured thereto a belt pulley 13. This shaft 12 is connected at one end by suitable gearing with a vertical shaft 14 which, in turn, is geared to the lower conveyer roller 4. At its opposite end the shaft 12 is connected by suitable gearing with a vertical shaft 15 which, at its upper end, is geared to the end of a shaft 16 forming an extension of the upper conveyer roller 5. The conveyer chains 6 are driven by means of a vertical shaft 17 geared to the driving shaft 12 and to the conveyer shaft 8. The husking rollers 10 are connected one to the other at their upper ends by spur gears 18 and one of the rollers is connected by beveled gearing with a shaft 19 journaled in a frame 1 and driven from the driving shaft 12 by a sprocket chain 20.

In Figs. 4 and 5 of the drawings we have illustrated a slightly modified form of the invention and have shown the same as comprising a frame 21 having mounted thereon and extending transversely thereof two conveyer rollers 22 and 23 arranged one above the other and having secured thereto at one end thereof snapping rollers 24. These rollers are carried by the shafts 25, to which the respective snapping rollers are also secured, and which are journaled at their inner ends on the frame 21 and are connected one to the other by spur gears 26. One of these shafts extends beyond the spur gear and has secured thereto a belt pulley 27. The outer end of the shaft of the lower roller 23 is journaled in a bearing 28 on the frame member and the outer end of the shaft of the upper roller 22 is journaled in a bearing 29 formed at the outer end of a bracket 30 or arm 30 supported near the opposite side of the frame 21, extending transversely thereto and having its outer end unsupported and spaced from the bearing 28 so as to leave an open space at the end of the conveyer rollers, beyond the snapping roll-

ers, through which the stalks of corn may pass. With this type of machine stalks of corn are fed end first into the conveyer rollers which move them longitudinally to bring the ears into engagement with the conveyer rollers and then move them transversely, that is, lengthwise of the conveyer rollers, to bring the ears into positions to be engaged by the snapping rollers. After the ears have been removed the stalks are delivered in a pile at the side of the frame and the ears may, if desired, be delivered to husking devices arranged beneath two snapping rollers in the same manner as described in connection with that form of the machine shown in Figs. 1 and 2. Inasmuch as the arrangement of the husking rollers may be similar to that in Figs. 1 and 2, it is not thought necessary to here illustrate or describe the same.

In Figs. 6 to 8 we have shown still another form of the invention in which the snapping rollers 31 are mounted on a frame 32 and are arranged near the discharge end of an endless conveyer 33 which extends across the frame from the operator's station to the snapping rollers. With this construction the stalks are placed on the conveyer 33 at the receiving end thereof and are moved transversely to bring the ears into engagement with the snapping rollers which remove the ear and deliver it to the husking rollers, and the stalks are then delivered in a pile as before described. The snapping roller is mounted on the main frame 33 while the upper roller is carried by the end of an arm 34 which extends from the rear edge of the frame and supports the upper snapping roller in such a manner that it will not interfere with the passage of the stalk between the two rollers. The snapping rollers and conveyers may be driven in any suitable manner. As here shown, they are driven by suitable sprocket chain connections from the main driving shaft 35.

The operation of the invention, in the several forms shown, will be clearly understood from the foregoing description, and it will be apparent that we have provided very simple mechanism for moving stalks of corn to the ear removing devices and for so positioning those stalks of corn as to bring the ears into proper relation to the removing devices, and that the ears can be removed and husked without mutilating the stalks, which are delivered in a pile from which they may be taken and reshoed or stored in any desired manner. While the mechanism is here shown as mounted on a stationary frame, it will be entirely obvious that this frame could be mounted on wheels and conveyed from point to point.

While we have shown and described certain embodiments of the invention, we wish it to be understood that we do not desire

to be limited to the details thereof, as various modifications may occur to a person skilled in the art.

Having thus fully described our invention, 5 what we claim as new and desire to secure by Letters Patent is:

1. In a device of the character described, a rotatable ear removing device, a structure having means to support stalks of corn in 10 horizontal position relatively to the opposite sides of the ear removing device and means operative substantially in the plane of said supporting structure for moving said stalk axially of said ear removing device to 15 align the same therewith and also transversely of said ear removing device to bring the ear into engagement therewith while said stalk is supported in substantially a horizontal position on said supporting structure.

20 2. In a device of the character described, a structure having means to support a stalk of corn in a substantially horizontal position, a rotatable ear removing device mounted on said structure, and means arranged in 25 advance of said ear removing device to engage the stalk of corn while it is in a horizontal position and move the same transversely toward said ear removing device and to move said stalk in the direction of its 30 length to bring the ear into a position to be engaged by said ear removing device.

3. In a device of the character described, a structure having means to support a stalk of corn in a substantially horizontal position, ear removing rollers mounted on said structure, a conveyer arranged in advance of said ear removing rollers to move a horizontal stalk of corn transversely to its length and substantially parallel with the axes of 40 said ear removing rollers and to move said stalk of corn in the direction of its length to bring the ear thereon into a position to be engaged by said ear removing device.

4. In a device of the character described, 45 a structure having means for supporting a stalk of corn in a substantially horizontal position, an ear removing device mounted on said structure, and means arranged in advance of said ear removing device to engage 50 a stalk of corn while the latter is supported in a substantially horizontal position by said structure and move the same transversely toward the ear removing device and to move said stalk of corn in the direction of its 55 length to bring the ear into a position to be engaged by said ear removing device.

5. In a device of the character described, 60 a structure having means to support a stalk of corn in a substantially horizontal position, an ear removing device mounted on said structure, conveying rollers mounted one above the other on said structure to receive the horizontal stalk of corn between them and having spiral ribs formed thereon, 65 and means for rotating said rollers in oppo-

site directions to cause said stalk of corn to be moved both in the direction of its length and transversely to its length to bring the ear into the proper position to be engaged by said ear removing device.

70

6. In a device of the character described, a structure having means to support a stalk of corn in a substantially horizontal position and a pair of snapping rollers carried by said structure and arranged one above the other, conveying rollers arranged in alignment with the respective snapping rollers and having spiral grooves, and means for rotating said conveying rollers in opposite directions to cause said stalk of corn to be 75 moved both longitudinally and transversely relatively thereto while in a substantially horizontal position.

7. In a device of the character described, 80 a structure having means to support a stalk of corn in a substantially horizontal position, a pair of conveying rollers mounted one above the other on said structure in substantially horizontal positions and having spiral ribs, means for rotating said rollers in opposite directions to move said horizontal stalk of corn both longitudinally and transversely relatively to the same, snapping 85 rollers arranged at the discharge ends of said conveying rollers, and means for so supporting one of said snapping rollers above the other that the stalk of corn may pass between the same parallel with their axes and be discharged from said supporting structure.

90

8. In a device of the character described, 95 a structure having means to support a stalk of corn in a substantially horizontal position, a pair of conveying rollers mounted one above the other on said structure in substantially horizontal positions and having spiral ribs, means for rotating said rollers in opposite directions to move said horizontal stalk of corn both longitudinally and transversely relatively to the same, snapping 100 rollers arranged at the discharge ends of said conveying rollers, and an arm carried by said supporting structure at a point beyond said snapping rollers and extending forwardly to form a support for one of said 105 snapping rollers, whereby the stalk of corn may pass between the snapping rollers and beneath said supporting arm.

9. In a device of the character described, 110 a structure having means to support a stalk of corn in a substantially horizontal position, a pair of conveying rollers mounted thereon, one above the other and in substantially horizontal positions and having spiral ribs, one of said rollers having its outer end supported in spaced relation to the other roller, so that a stalk of corn may be placed transversely between said rollers, snapping rollers 115 arranged at the discharge ends of said conveying rollers and means for actuating said 120 conveying rollers and means for actuating said 125 conveying rollers and means for actuating said 130 conveying rollers and means for actuating said

snapping rollers and said conveying rollers to cause said stalk of corn to be moved both transversely and longitudinally to bring the ear into engagement with said snapping rollers.

10. In a device of the character described, a structure having means to support a stalk of corn in a substantially horizontal position, a pair of conveying rollers rotatably mounted on said structure and arranged one above the other, said rollers having spiral ribs, the uppermost roller having one end suspended above the lower roller to enable said stalk of corn to be placed transversely between said rollers; snapping rollers rigidly secured to the conveying rollers at the discharge ends thereof, and means to actuate said conveying rollers to move said stalk of corn both transversely and longitudinally thereof.

15. 11. In a device of the character described, a supporting structure, a pair of conveying rollers rotatably mounted on said structure and arranged one above the other, said rollers having spiral ribs, the uppermost roller having one end suspended above the lower roller, whereby a stalk of corn may be placed transversely between said rollers, snapping rollers rigidly secured to said conveying rollers at the discharge ends thereof, and conveyers arranged on opposite sides of said conveyer rollers to move the end portions of said stalk of corn along with that part thereof which is engaged by said conveying rollers.

20. 12. In a device of the character described, a supporting frame comprising a main portion, conveyor rollers mounted on said main portion and having spiral ribs, snapping rollers rigidly secured to said conveyer rollers at their discharge ends, one of said conveyer rollers and its snapping roller being journaled on the main portion of said supporting frame, a shaft journaled on said frame, projecting above the main portion thereof and connected with the other conveyer roller and its snapping roller, and means for actuating said conveyer rollers and the snapping rollers.

25. 13. In a device of the character described, a frame having a main portion, a conveyer roller extending transversely of said main portion of said frame and having spiral ribs,

and a snapping roller arranged at the discharge end of said conveyer roller, said supporting frame also having a rear portion, a shaft journaled on said rear portion of said frame and extending forwardly above the main portion of said frame, a second conveyer roller and a second snapping roller mounted on said shaft, said shaft being so arranged with relation to the main portion of said frame that a stalk of corn may be discharged from said conveyer rollers beneath said shaft, and means for actuating said rollers.

30. 14. In a device of the character described, a supporting frame comprising a table, conveyer rollers extending transversely of said table, having spiral ribs and adapted to receive a stalk of corn between them and to impart both longitudinal and transverse movement to said stalk of corn, snapping rollers arranged at the discharge ends of said conveyer rollers, said table having an opening therein adjacent to said snapping rollers, and husking rollers arranged beneath said opening to receive ears of corn from said snapping rollers, said supporting structure being so arranged that the stalks of corn discharged from said conveyer rollers may be moved beyond said snapping rollers and discharged from said table.

35. 15. In a device of the character described, a supporting frame comprising a forward portion, a conveyer moving transversely of said forward portion, said structure also comprising an upright portion arranged in the rear of said forward portion and having a forwardly extending part, a pair of ear removing devices supported respectively by said forward portion of said frame and the forwardly extending part of said rearward portion thereof, whereby a stalk of corn may be moved transversely of the forward portion of said supporting structure to bring the ear into engagement with said ear removing devices and then be discharged into a space between the forward and rearward portions of said structure.

40. In testimony whereof, we affix our signatures hereto.

SAMUEL E. MORRAL.
WILLIAM W. MORRAL.
